UNITED STATES PATENT OFFICE

147,309

DESIGN FOR A FLOOR POLISHER

Te Lou Tchang, New York, N. Y.

Application May 17, 1946, Serial No. 129,766

Term of patent 14 years

(Cl. D9—2)

To all whom it may concern:

Be it known that I, Te Lou Tchang, a citizen of the Republic of China and a resident of the city of New York, in the county of New York and State of New York, have invented a new, original, and ornamental Design for Floor Polisher, of which the following is a specification, reference being had to the accompanying drawing, forming a part thereof.

Fig. 2 is a front view thereof, and

Fig. 3 is a top view thereof with the handle omitted for convenience of illustration.

I claim:

The ornamental design for a floor polisher, substantially as shown.

TE LOU TCHANG.
